UNITED STATES PATENT OFFICE.

ELЛИCK H. GOLLINGS, OF CHICAGO, ILLINOIS.

ROTARY POWER DEVICE.

1,378,856.

Specification of Letters Patent. Patented May 24, 1921.

Application filed August 11, 1919. Serial No. 316,910.

To all whom it may concern:

Be it known that I, ELLICK H. GOLLINGS, a citizen of the United States, and a resident of the city of Chicago, in the county of Cook and State of Illinois, have invented certain new and useful Improvements in Rotary Power Devices; and I do hereby declare that the following is a full, clear, and exact description of the same, reference being had 5 to the accompanying drawings, and to the numerals of reference marked thereon, which form a part of this specification.

This invention has reference more particularly to a device comprising inner and outer 15 rotary members which coöperate to provide gradually expanding chambers at one side of the device which after maximum expansion, transfer the contents to gradually contracting chambers at the opposite side of the device, and enable the device to operate as a 20 pump by applying power to the rotary members or to be used as a motor by introducing a fluid under pressure into the expandable chambers.

25 An object of the invention is to provide an improved form of rotary pump or motor comprising inner and outer rotary members having pressure chambers or pockets therebetween and a central valve element for affording communication with the chambers or pockets and regulating the supply and discharge of fluid thereto and therefrom.

Another object of the invention is to simplify and cheapen the construction of such 35 devices more particularly by providing interengaging teeth or projections having flat engaging surfaces for driving engagement of one member with the other.

A further object of the invention is to provide 40 a construction in which the teeth have a sliding movement relatively to each other along parallel lines thereby providing a large contact area and consequently relatively little wear or leakage.

45 It is also an object of the invention to provide a device of the type set forth with equal numbers of teeth on both inner and outer rotary members.

A further object of the invention is to provide 50 a device of the type set forth with equal numbers of teeth on both inner and outer rotary members.

An additional object of the invention is to provide a device of the type set forth

with a series of tangentially directed teeth 55 or projections.

Other and further important objects of this invention will be apparent from the disclosures in the specification and drawings.

The invention (in a preferred form) is 60 illustrated in the drawings and hereinafter more fully described.

On the drawings:

Figure 1 is a side elevation of a device embodying the features of the present invention.

Fig. 2 is an end view of the same.

Fig. 3 is a section on the line 3—3 of Fig. 1.

Fig. 4 is a section on the line 4—4 of Fig. 3.

Fig. 5 is a section on the line 5—5 of Fig. 1, with parts removed.

Fig. 6 is a side elevation of the rotor of the device.

Fig. 7 is a section on the line 7—7 of Fig. 3.

Fig. 8 is a section on the line 8—8 of Fig. 1.

Figs. 9 and 10 are similar views to Fig. 3 showing the parts in different positions.

As shown on the drawings:

The reference numeral 1 indicates a base for supporting the device which has the spaced standards 2, each of which has a 85 clamp bearing 3, at the upper end having a cylindrical opening therethrough. Intermediate of the standards 2, is a hollow drum or cylinder 4, with the hollow shafts 5 and 6, extending eccentrically from the end walls 90 thereof through the clamp bearings so that the shafts are in alinement and the axis thereof is at one side of the axis of the cylinder or drum 4. Preferably, the shafts 5 and 6 are formed integrally with the cylinder 4 as is shown.

A wheel or rotor 7 is mounted to turn on the drum 4 and is provided with a series of tangentially directed projections 8. Mounted upon the inner ends of the shafts 5 and 6 to rotate thereon is a rotary casing 9, comprising a drum 10 and end plates 11 secured thereto by bolts 12. Each of said end plates has a sleeve 13 attached thereto, one of which sleeves is journaled on the shaft 5 100 and the other on the shaft 6.

The plates 11 are carefully spaced and constructed so as to contact with the outer

faces of the drum 4 and wheel 7 therebetween, sufficiently closely to avoid leakage therebetween and at the same time permit differential rotation of the casing 9 and rotor 5 on the drum 4.

Within the drum 10 are provided inwardly extending teeth 15 and intermediate projections 16 for engagement with the projections 8 of the rotor. These teeth and 10 projections may be formed either integral with the drum 10 or on a separate ring 14 as shown in the accompanying drawings. The numbers of teeth on these two parts being the same, they both rotate at exactly the same 15 speed.

In view of the fact that both the rotor and the ring 14 rotate at the same speed, a sliding action instead of a rolling action occurs between the teeth with the result that 20 the contact surfaces may be made much larger. Further, the contact surfaces on the teeth of both the rotor 7 and the ring 14 may be made flat.

From inspection of Figs. 3, 9, and 10, 25 it will be seen that the only curved surfaces are 33 and 35, between the teeth 15 and 8, respectively. Although contact is made with these surfaces such contact is only necessary for a short interval since 30 at all other times the flat surfaces 17 and 18 are in contact and prevent passage of fluid through the lower part of the device. In the upper part of the device sliding parallel contact between the surfaces 19 and 35 20 is relied upon entirely to separate the inlet and exhaust chambers.

The action of the device may be best understood by following one pair of teeth around through one complete revolution. 40 Take the pair of teeth 8 and 15 at the lower left hand corner of Fig. 3. As the rotor 7 and rotating member 14 turn in an anti-clockwise direction the end surface 34 of the tooth 15 approaches the surface 35 of 45 the rotor 7 as shown in Fig. 9 until they contact as shown in Fig. 10. Substantially simultaneously the surface 17 of the tooth 8 contacts with the surface 18 of the member 16. Further rotation causes separation 50 of the surfaces 32 and 33 and the teeth 8 and 15 do not contact again until the surface 20 of the tooth 15 meets the surface 19 of the tooth 8. Then a sliding action takes place until the tooth 8 slides off the 55 end of the tooth 15. During this movement the surfaces remain in sliding contact since the surfaces retain their parallel relation during such movement owing to the fact that the two members 7 and 14 rotate at 60 the same speed. After the surfaces 19 and 20 separate, the cycle of operations commences over again.

It will be observed that in the upper part 65 of the device two pairs of teeth 8 and 15 are always in contact through their surfaces

19 and 20. In the lower part of the device there is always contact between one or more of the following pairs of contacts: 17, 18; 34, 35 or 32, 33; so that two chambers are formed in the device, one for the admission 70 of fluid and the other for the exhaust of fluid therefrom.

By reason of the parallelism maintained between these contacting surfaces leakage is reduced to a minimum and smooth, even 75 operation is obtained. In addition to the parallel sliding action of the contacting surfaces the use of equal numbers of teeth on both rotor 7 and ring 14 enables certain of the surfaces on both rotor and ring to be 80 made parallel to each other. Thus the surfaces 17 and 19 on each tooth 8 are parallel while the surfaces 18 and 20 are also parallel so that they may be cut at a single operation. In view of this fact and also since 85 the surfaces 32, 33 and 35, are concentric with the parts on which they are formed the construction is greatly simplified and cheapened.

The drum 4 is provided with an outlet 90 port 21 and an inlet port 22 adapted to register with ports 23 in the rotor arranged between each projection 8, thereon.

A central partition 24 divides the drum 4 into two chambers communicating with the outlet port 21 and the hollow shaft 5 and the other with the inlet port 22 and the hollow shaft 6.

At their outer ends each sleeve 13 is provided with a gland 27 of any suitable construction for preventing fluid escaping between the sleeves 13 and the shafts 5 and 6.

These sleeves 13 are arranged to rest in half bearings 25 arranged between the plates 11 and the glands 27, on the upper ends of standards 26 which serve to steady the machine in its rotation about the fixed shafts 5 and 6.

Provision is preferably made for adjusting the position of the bearings 3, so that the greater part of the weight is taken by the shafts 5 and 6, and the half bearings 25, only partially support and steady the machine. For this purpose the standards 2 are clamped to the ends of the base 1 by bolts 28 so that their position both vertically and laterally may be varied within small limits. An adjusting bolt 31 is provided for changing the height of the bearings 3 as desired.

Power may be taken from or applied to the rotary casing by means of any suitable means such as an annular gear 28 secured to a series of lugs 29 on the outer face of one of the plates 11. These lugs may conveniently be recessed as shown in Fig. 7 for the reception of the gear 28 which is thus held against lateral movement. Bolts 30 are provided for attaching the gear to the lugs.

The operation is as follows:

When used as a pump, power is applied to rotate the casing 9, in the direction indicated by the arrow in Fig. 3. As each tooth 8 of wheel 7 reaches the lower-most position, its outer surface 17 engages the surface 18 of the adjacent projection 16 on the drum 10. At the same time the teeth diametrically opposite thereto contact with the surface of the inwardly projecting teeth 15. In devices heretofore constructed the engaging surfaces have been made curved so that the teeth roll one against the other and engage along a single line which occasioned considerable wear and was not effective to prevent leakage between the intake and outlet sides of the device. With the present construction, however, the sides of the projections and teeth are flat surfaces which come flat together as the device is operated. This construction not only avoids excessive wear but also insures a tight joint which will prevent leakage therethrough.

The increasing size of the pockets between the wheel 7 and the ring 14 creates a suction which draws the fluid therein and as the compartment reaches the upper position the tip of the tooth 8 engages the tip of the adjacent tooth 15 at the top of the ring 14 and separates the compartment formed therebetween from the space between the teeth on the intake side of the pump. Communication between the intake and discharge sides of the device through the drum 4, is prevented by the partition 24. Further rotation of the casing 9 first opens communication between this chamber and the discharge side of the device and then produces a gradual reduction in the size of the sockets on the discharge side and thereby results in forcing fluid through the ports 23, 21 into the outlet pipe 5.

Obviously this device may be used as a motor by applying fluid under pressure which reverses the operation of the parts.

I am aware that various details of construction may be varied through a wide range without departing from the principles of this invention, and I therefore do not purpose limiting the patent granted otherwise than necessitated by the prior art.

I claim as my invention:

1. In a device of the class described the combination of a hollow rotary member having internally projecting teeth, the surfaces of said teeth being at an acute angle to the circumference of the hollow member, a rotor mounted eccentrically therein and having teeth adapted for engagement with the teeth of the rotary member to provide expandable

inlet compartments at one side of the device and contractible outlet compartments at the opposite side of the device, a stationary hollow cylinder arranged axially of the rotor having a transverse partition therein, a hollow shaft secured to each side of the cylinder, a clamping bearing for supporting the outer end of each shaft, a sleeve around each shaft secured to and rotating with the hollow rotary member, and a bearing for external engagement with each sleeve.

2. In a device of the class described the combination of a hollow rotary member having two sets of internally projecting teeth of different sizes, a rotor mounted eccentrically therein and having teeth adapted for alternate engagement with the teeth of the rotary member to provide expandable inlet compartments at one side of the device and contractible outlet compartments at the opposite side of the device, a stationary hollow cylinder arranged axially of the rotor having a transverse partition therein, a hollow shaft secured to each side of the cylinder, a clamping bearing for supporting the outer end of each shaft, a sleeve around each shaft secured to and rotating with the hollow rotary member, a bearing for external engagement with each sleeve, and a gland between each clamping bearing and the adjacent sleeve bearing.

3. In a device of the class described the combination of a hollow rotary member having internally projecting teeth, the working surfaces of said teeth being at an acute angle to the circumference of the hollow member, a rotor mounted eccentrically therein and having teeth adapted for engagement with the teeth of the rotor member, to provide expandable inlet compartments at one side of the device and contractible outlet compartments at the opposite side of the device, a stationary hollow cylinder arranged axially of the rotor having a transverse partition therein, a hollow shaft secured to either side of the cylinder, a clamping bearing for supporting the outer end of each shaft, a sleeve around each shaft secured to and rotating with the hollow member, a bearing for external engagement with each sleeve, and means for adjusting the position of each clamping bearing with respect to the adjacent bearing.

In testimony whereof I have hereunto subscribed my name in the presence of two subscribing witnesses.

ELICK H. GOLLINGS.
